UNITED STATES PATENT OFFICE.

ALBERT MATHIAS, OF EL PASO, TEXAS.

GARMENT.

1,121,383.

Specification of Letters Patent. Patented Dec. 15, 1914.

Application filed October 23, 1913. Serial No. 796,883.

To all whom it may concern:

Be it known that I, ALBERT MATHIAS, a citizen of the United States, residing at El Paso, in the county of El Paso and State 5 of Texas, have invented certain new and useful Improvements in Garments, of which the following is a specification.

This invention relates to improvements in garments, particularly trousers, overalls and 10 similar garments of that character having a waist-band and a front placket or fly, the object of the invention being to provide fastening means for adjusting the waist-band to hold the garment supported upon 15 the wearer and to simultaneously draw the meeting edges of the fly or placket into proper position, the construction of the fastening or supporting means being such as to imitate or present the appearance of the 20 use of an ordinary belt.

A further object of the invention is to provide a garment having fastening or supporting means of the character described, including straps forming extensions from 25 the ends of the waist-band, one of which straps is adapted to be passed through an opening in the waist-band so that the straps may be extended in opposite directions on the outside of the waist-band to points adjacent the sides of the garment and there 30 suitably fastened in position, by which the waist-band may be easily and conveniently contracted as desired and the garment properly fitted upon the wearer.

35 A still further object of the invention is to provide a garment having a fastening or supporter of the character described including cooperating members for retaining the straps in position, which members are 40 adapted to simulate the appearance of the usual front buckle and the waist-band adjusting straps at the sides of the garment.

With these and other objects in view, the 45 invention consists of the features of construction, combination and arrangement of parts, hereinafter fully described and claimed, reference being had to the accompanying drawings, in which:—

Figure 1 is a front view of the waist portion of a garment embodying my invention; 50 Fig. 2 is a similar view with the outer strap embodied, and showing certain features of construction; Fig. 3 is a detail section on

the line 3—3 in Fig. 1; and Fig. 4 is a detail section on the line 4—4 in Fig. 1.

55

Referring to the drawings, 1 designates a pair of overalls, trousers or other similar garment, having a waist-band 2 and divided at the front to provide a placket or fly, the overlapping meeting edges of which are indicated at 3 and 4. These meeting edges of the placket or fly may be united as usual by buttons or other suitable fasteners 5. The ends of the waist-band 2 are adapted to overlap at the front of the garment in 60 line with the placket or fly, and one of the meeting edges, such as the outer end 6, of the waist-band is provided substantially in line with the meeting edge 4 of the placket or fly with a slit or opening 7, and such 65 end of the waist-band is preferably provided with a reinforcing member 8. This reinforcing member may consist of a length of wire disposed between the plies of the 70 waist-band and curved to give proper form thereto and adapted to render the said portion of the waist-band relatively stiff or 75 rigid for proper guidance and connection of the waist-band straps, as hereinafter described. As shown, the reinforcing wire 8 80 has its ends bent backwardly to provide blunt portions 9 to prevent it from penetrating or puncturing the fabric. The said outer end 6 of the waist-band, which is 85 adapted to lap over the inner end 9 of the waist-band, is provided with a fastening strap or extension 10, and the end 9 is provided with a similar fastening strap or extension 11. In adjusting the waist-band to 90 the person of the wearer, the strap 11 is passed outwardly through the slit or opening 7 and the respective straps 10 and 11 95 extended in opposite directions around the front of the waist-band, the reinforcing member 8 rendering the end 6 of the waist-band sufficiently stiff or rigid to permit the strap 11 to be passed through the opening 7 with ease and facility.

It will be understood from the foregoing 100 description that by extending the straps 10 and 11 in the manner described, the waist-band 2 may be contracted to the desired degree to fit about the waist of the wearer and support the garment in the proper position upon the person, and that such adjustment 105 of the said straps also brings the meeting

edges 3 and 4 of the fly or placket in proper relative position to be united by the buttons or other fasteners 5. When the straps are so extended they give the general appearance of the use of the ordinary belt, as well as a desirable finish to the waist-band of the garment.

The free ends of the straps 7 and 8 are adapted to be secured in position by clamps, 10 clasps or fastening members 12, which are preferably applied to short tabs 13, secured to the waist-band adjacent the sides or hip portions thereof, whereby the waist-band will be held securely in adjusted position. 15 These fastenings or clasps are so arranged as to simulate the usual adjusting devices at the sides of trousers or a similar garment for the purpose of taking up any slack in the waist-band, thus giving an attractive 20 finish to the waist-band and garment as a whole and at the same time further giving the impression of the use of ordinary adjusting devices in connection with an outside belt. For the purpose of holding the 25 secured straps against relative movements and giving a further desirable ornamental- 30 ity of finish I may provide an imitation buckle plate 14 to overlie the strap 10 in line with the fly or placket and to conceal the opening or slit 7. As shown, this buckle plate is provided with tongues 15 stamped therefrom and adapted to be passed through the slit or opening 7 and bear upon the rear 35 side of the strap 10 to hold the buckle plate in position, the buckle plate and tongues firmly engaging the straps and holding the same from relative sliding motions, thereby relieving the fastenings at the ends of the straps from overstrain.

40 By reason of the fact that the slit 7 is centrally located with respect to the garment, or with respect to the structure forming the device of my invention, it is possible to dispose a buckle simulating or 45 appearing plate over the slot 7 in such a manner as not only to conceal the slot but also to carry out the simulation of a belt, independent of the garment.

From the foregoing description, taken in 50 connection with the accompanying drawings, it will be seen that my invention provides a fastener or supporter of the character described which is simple of construction, affords the advantages set forth, and 55 by means of which the waist-band and portions of the fly or placket may be easily and conveniently adjusted and the garment held securely in place. The supporter provides an inexpensive adjunct which may be used 60 with advantage upon comparatively cheap garments, such as overalls, to add to the strength and finish thereof.

Having thus described my invention, I claim:

1. A garment having a front placket and 65 a waistband portion provided with a slit intersecting the placket opening, the margins of the slotted portion being arranged to overlap and the outwardly overlapping margin having an opening substantially at 70 its juncture of overlap with the inwardly lapping margin, said waist band having belt strap extensions extending from the ends of said band, the strap of the inwardly lapping waist band end being adapted for pro- 75 jection through said opening and being adapted to be disposed exteriorly throughout its length against the outwardly lapping waist band, the strap of the outwardly lapping waist band being adapted to be disposed 80 against the exterior of the inwardly lapping band throughout the length of said strap of the outwardly lapping band, and means for attaching the free ends of the straps to the garment, substantially as described. 85

2. A garment having a waist portion provided at its front with a placket, a waistband having one of its ends provided with a vertical slit at the top of the outer ply of the placket, a reinforcement inclosed in said 90 slotted end of the waist-band, belt straps forming extensions from the ends of the waist-band and extending longitudinally to equal degrees on opposite sides of the slit and adapted to be extended in opposite directions 95 along the outside of the front of the waistband to points adjacent the sides of the garment, one of said straps being adapted for passage through said slit, and means for attaching the free ends of the straps to the 100 garment.

3. A garment having a waist portion provided at its front with a placket, a waistband having one of its ends provided with a vertical slit at the top of the outer ply of 105 the placket, belt straps forming extensions from the ends of the waist-band and adapted to be extended in opposite directions along the outside of the front of the waistband to points adjacent the sides of the garment, one of said straps being adapted for 110 passage through said slit a plate carried by the slotted end of the waist-band and having tongues for insertion into said slit to clamp the plate in position and frictionally holding the straps against relative movement, and means for attaching the free ends of the straps to the garment. 115

In testimony whereof I affix my signature in presence of two witnesses.

ALBERT MATHIAS.
